NUT

Donald J. Reid, Pleasant Ridge, Mich., assignor to Kelsey-Hayes Company, Romulus, Mich., a corporation of Delaware

Filed Nov. 5, 1965, Ser. No. 88,011

Term of patent 14 years

(Cl. D54—9)

FIGURE 1 is a side elevational view of a nut showing my new design;

FIGURES 2 and 3 are elevational views from opposite ends of the nut;

FIGURE 4 is a side elevational view of the nut taken from a different direction than FIGURE 1;

FIGURE 5 is a sectional view of the nut taken along the line 5—5 in FIGURE 4; and

FIGURE 6 is a perspective view of the nut.

I claim:

The ornamental design for a nut, substantially as shown.
